CLAIM

The ornamental design for a wearable electronic display device, as shown and described in FIGS. 1–12.

DESCRIPTION

FIG. 1 is a left front perspective view of a wearable electronic display device;

FIG. 2 is a right front perspective view thereof;

FIG. 3 is a bottom front perspective view thereof;

FIG. 4 is a rear view thereof;

FIG. 5 is a top front perspective view thereof; and

FIG. 6 is a left side elevation thereof.

FIG. 7 is a right front perspective view of a wearable electronic display device of FIG. 1, shown in an alternate position;

FIG. 8 is a top perspective view of FIG. 7;

FIG. 9 is a side elevation thereof;

FIG. 10 is a top view thereof;

FIG. 11 is a bottom view thereof; and,

FIG. 12 is an alternative perspective view thereof.

The broken lines shown are included for the purpose of illustrating portions of the wearable electronic display device that form no part of the claimed design. Line shading represents contours and not surface ornamentation.
